UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LAMP CASING.

Application filed June 29, 1921. Serial No. 431,335.

To all whom it may concern:

Be it known that I, CROMWELL A. B. HALVORSON, Jr., a citizen of the United States, residing at Lynn, in the county of Essex, 5 State of Massachusetts, have invented certain new and useful Improvements in Lamp Casings, of which the following is a specification.

My invention has reference to lamp casings. More specifically, it relates to casings for supporting lamp units on top of standards.

An object of my invention is to provide a simple unit of this character made of an 15 insulating material, such as porcelain, thereby eliminating numerous parts heretofore employed to insulate the lamp from the standard, and thereby greatly simplifying the construction of the electrical connection 20 for the lamp.

Another object of my invention is to provide a rugged lamp casing, capable of carrying the necessary weight, which is not easily broken, and which may withstand the elements 25 indefinitely without deterioration or impairment of its efficiency and ornamental effect.

In the accompanying drawings, Fig. 1 is an elevation of my lamp casing, shown 30 partly in vertical section, with one type of lamp socket and with the means for securing the casing to the standard illustrated. Fig. 2 is a top view of the securing ring and Fig. 3 is an enlarged detail view of Fig. 2.

Referring to the drawings, the numeral 35 10 indicates a lamp casing made of insulating material, preferably porcelain. At its base the casing is provided with an external flange 11 which serves as a securing means 40 to a standard 12 as will appear hereinafter. The top 13 of the lamp casing is of larger diameter than its base, and is formed with a suitable ledge 14 on which the lamp globe, not shown in the figure, may be supported 45 in the usual manner.

The casing 10 is formed with two chambers 15 and 16, which are separated by a wall 17 substantially at right angles to the axis of the casing and integral with the 50 casing. The chamber 16, which is located on the top side of the wall 17, that is, at the enlarged end of the casing, houses a lamp socket 18, or any other suitable type of electrical connection for the lamp. The 55 chamber 15, which is on the lower side of

the wall 17, houses the electrical terminals for the socket and forms a passageway for the leads thereto, not shown in the drawing. The particular type of lamp socket 18 illustrated forms no part of my present invention, since any suitable socket may be employed to cooperate with the lamp unit used. However, this socket illustrates the simplicity of construction of the lamp socket and its connections in my lamp casing, in which the casing itself insulates the several socket members and supports them, thereby eliminating separate insulating and supporting members.

The wall 17 is formed with an elevated circular platform 19 in the chamber 16, having a slot 20 on a diameter thereof. The socket receptacle 21, which is provided with suitable bayonet slots 22, is rigidly secured on the platform 19 by screws 23 and 24, 70 shown in broken lines in Fig. 1. The screw 24 forms a part of one side of the electric circuit for the lamp, and at one end is in electrical contact with the receptacle 21. This screw extends through the wall 17 into 75 the chamber 15, and at this end is held in place by a nut 25, which is machined to form a terminal. The other side of the electric circuit in the socket consists of a screw 26, extending through the wall 17, 80 having a nut 27, similar to nut 25, in the chamber 15, and securely holding a flexible conductor 28 in the slot 20. The conductor 28 is made of a flat strip of copper which is doubled on itself, and supports a contact 85 29. The contact 29 has a stem 30 extending into a hole in the wall 17 located in the axis of the lamp and the contact 29 and conductor 28 are normally urged into the receptacle 21 by a spring 31, surrounding the 90 stem 30, and seated in a thimble 32. The terminals 25 and 27 are each respectively provided with suitable openings 33, 34 and screws 35, 36 for securing the electric circuit leads thereto. The casing 10 is provided 95 with suitable drainage openings 37 leading from the chamber 20.

The standard 12 is provided with a flange 38 at its top, similar to the flange 11 on casing 10, which forms a shoulder on which 100 the lamp casing 10 rests when mounted on the standard 12. The casing is secured in this position by a clamping ring, which consists of two semi-circular members 39 and 40, which are internally machined to fit 110

over the flanges 11 and 38 as shown in Fig. 1. The members 39, 40 are hinged to each other by a bolt 41, the members being cut and fitted as shown in Fig. 3. At their free ends, the members 39 and 40 are respectively provided with lugs 42 and 43. A screw bolt 44 extends through these lugs, by means of which the members 39 and 40 are caused to clamp the casing to the standard in a manner readily understood.

While I have described my invention as embodied in concrete form in accordance with the provisions of the patent statutes, it should be understood that I do not limit my invention thereto, since various modifications thereof will suggest themselves to those skilled in the art without departing from the spirit of my invention, the scope of which is set forth in the annexed claims.

20. What I claim as new and desire to secure by Letters Patent of the United States, is:

1. In a highway light unit fixture, a lamp casing formed of insulating material hav-

ing an upper and a lower inner chamber, a wall separating the two chambers, a lamp socket in the upper chamber supported by said wall and insulated thereby, and electric terminals extending through said wall into the lower chamber, the upper part of said casing formed into a holder for supporting a globe and a drain duct extending from the socket chamber through the wall of the casing.

2. In combination, a lamp casing formed of insulating material having an upper and a lower inner chamber, a wall separating the two chambers, a lamp socket in the upper chamber supported by said wall and insulated thereby, electric terminals extending through said wall into the lower chamber, a standard, and a clamping ring for securing the casing to the standard.

In witness whereof, I have hereunto set my hand this 25th day of June, 1921.

CROMWELL A. B. HALVORSON, JR.
